(73) Assignee: **Honda Giken Kogyo Kabushiki Kaisha**, Tokyo (JP)

The ornamental design for, an exterior surface configuration of a motorcycle rear combination light assembly, as shown and described.

(**) Term: **14 Years**

DESCRIPTION

(21) Appl. No.: **29/133,401**

FIG. 1 is a front view of an exterior surface configuration of a motorcycle rear combination light assembly, showing our new design;

(22) Filed: **Nov. 30, 2000**

FIG. 2 is a top plan view thereof;

(51) LOC (7) Cl. **26-06**

FIG. 3 is a right side elevational view thereof;

(52) U.S. Cl. **D26/28**

FIG. 4 is a perspective view of thereof; and,

(58) Field of Search D26/28-36; 362/61, 362/80, 83.4, 267, 269, 278, 327, 328, 329, 330-340

FIG. 5 is a perspective view illustrating the present invention with the environment of the invention set forth in broken lines.

(56) **References Cited**

Features shown in broken lines depict the environment and do not form part of the claimed design.
